C. W. HAZELETT,
DRY CELL,
APPLICATION FILED MAY 9, 1919.

Patented Feb. 24, 1920.

FIG. 1

FIG. 2

INVENTOR
C. W. HAZELETT
BY *Dr. J. Adams*,
ATTORNEY

UNITED STATES PATENT OFFICE.

CLARENCE W. HAZELETT, OF LAKEWOOD, OHIO, ASSIGNOR TO NATIONAL CARBON COMPANY, INC., A CORPORATION OF NEW YORK.

DRY CELL.

1,331,761.

Specification of Letters Patent. Patented Feb. 24, 1920.

Application filed May 9, 1919. Serial No. 295,987.

To all whom it may concern:

Be it known that I, CLARENCE W. HAZELETT, a citizen of the United States, residing at Lakewood, in the county of Cuyahoga and State of Ohio, have invented a certain new and useful Improvement in Dry Cells, of which the following is a full, clear, and exact description.

This invention relates to dry cells.

10 It is well known that dry cells are made from zinc cans which contain an electrolyte mix tamped around a central carbon electrode with a paper or other bibulous lining between the mix and the can. When paper 15 is used as a bibulous lining it is the usual custom to use a lining that is considerably longer than the compacted mass of mix in the can, so that it may be folded over or otherwise crumpled into position on top of 20 the mix. To complete the cell a layer of sand is usually added on top of the folded-over portion of the lining, and then a seal 7, as molten pitch, is poured on top of the sand until it is substantially level with the top 25 of the can. With dry cells made as specified it is found that there is considerable trouble experienced through the corrosion of the zinc immediately below the layer of sand. The corrosion at this point is much 30 more rapid than in other portions of the cell, and frequently the top portion of the zinc will be entirely separated from the lower portion before the useful life of the cell would otherwise have terminated.

35 It has been found that the excessive corrosion of the zinc near the top is caused by the greater concentration of electrolyte in this neighborhood, due to the increased amount of electrolyte in the crumpled-over 40 portion of the lining. During the action of the cell the surface of the paper lining adjacent the zinc is depleted of electrolyte and this must be supplied by the diffusion of other electrolyte from the interior portion 45 of the lining and from the adjacent mix. Since there is a greater mass of the paper lining at the top due to the crumpled-over portion, the electrolyte will diffuse more rapidly to raise the concentration of the 50 electrolyte in the surface adjacent the zinc, than it will in the lower portions of the lining where there is only one thickness of lining. Consequently there results a higher concentration of electrolyte adjacent the surface of the zinc where the lining is folded

over the top of the mix. The difference in concentration between the top of the zinc and the other portions causes continual electrolytic action that eventually dissolves away the zinc at the top.

60 It has also been found that the excessive corrosion near the top is caused in part by the good conducting path between the electrode and the zinc furnished by the bent-over portion of the lining which of course 65 is more or less saturated with good conducting electrolyte.

70 My improvement aims to overcome this disadvantage and the manner in which this is accomplished will now be described, reference being had to the drawings in which:

Figure 1 illustrates a dry cell having the improvement.

75 Fig. 2 shows a modified method of applying the invention.

The upper ends of the zinc cans 1 are coated at 2 for a portion of the way down, with some insulating and impervious material, such as the various liquid celluloid compounds or celluloid cements, pitch, 80 tar, etc. The coating may be applied by means of a brush or the can may be inverted and dipped in the coating solution and held preferably in the inverted position until the cement or other coating 85 dries. If the can is dipped as specified there will be a coating on the outside, but this will not be objectionable as it will be covered by the usual paper jacket. However, if desired, the coating may be removed 90 as soon as the can is taken out of the solution, by wiping it off.

95 The coating 2 may be applied to the can 1 either before or after the mix 3 is tamped inside the bibulous lining 4 within the zinc can. Preferably it is applied before the tamping process is applied to the cell. In the cell shown in the drawings the usual layer 5 of sand or other suitable material is placed on top of the bent-over portion 6 of 100 the lining, and the usual seal 7 is added to this. There, of course, will be a suitable binding post attached to the zinc 1, but this has not been shown so as to make clear the invention which involves the use of the coating 105 material near the top of the zinc. In Fig. 2 I have shown a coating 8 applied near the top of the can on the inside by means of a suitable brush.

110 When the top of the zinc is coated with the

insulating and impervious material as specified, the zinc is protected from corrosion adjacent the folded-over portion of the lining, because the insulated coating extends below such portion. This increases the path of the current and of the electrolyte sufficiently to very materially reduce corrosion at this point.

While I have described more or less specifically my improvement, it will be understood that this is by way of example and that various modifications may be made without departing from the spirit of the invention.

Having described my invention, what I claim is:

1. In dry cells, a zinc can, an electrolyte mix in said can, a bibulous lining between

the mix and the can, said lining being folded over the top of the mix, a layer of impervious, non-conducting material adjacent the inside surface of the can and extending substantially below said folded-over portion of the lining whereby corrosion is reduced thereat.

2. In dry cells, a zinc can, an electrolyte mix in said can, a bibulous lining between the mix and the can, said lining being folded over the top of the mix, a coating of impervious non-conducting material secured to the can and extending substantially below the folded over portion of the lining whereby corrosion is reduced thereat.

In testimony whereof, I hereunto affix my signature.

C. W. HAZELETT.
